(57) **CLAIM**

The ornamental design for an infrasonic vibration massager, as shown and described.

DESCRIPTION

FIG. 1 is a perspective view of an infrasonic vibration massager, showing my new design;
FIG. 2 is a top plan view thereof;
FIG. 3 is a bottom plan view thereof;
FIG. 4 is a side elevational view thereof, the other side being a mirror image;
FIG. 5 is a front end elevational view thereof; and,
FIG. 6 is a rear end elevational view thereof.
